FIG. 1.

FIG. 2.

Cassandra K La Ruea
INVENTOR

UNITED STATES PATENT OFFICE

96,124

DESIGN FOR A CAPE

Cassandra K. La Ruea, New York, N. Y.

Application May 14, 1935, Serial No. 56,832

Term of patent 3½ years

To all whom it may concern:

Be it known that I, Cassandra K. La Ruea a citizen of the United States of America, residing in Manhattan, county of New York, and State of New York, have invented a new, original, and ornamental Design for a Cape, of which the following is a specification, reference being had to the accompanying drawing, forming part thereof, wherein,

I claim:

The ornamental design for a cape, substantially as shown.

CASSANDRA K. LA RUEA.
